UNITED STATES PATENT OFFICE.

KATHARINE S. BANNING, OF LOS ANGELES, CALIFORNIA.

DESIGN FOR A COMFORT-BAG.

51,913.

Specification for Design.

Patented Apr. 2, 1918.

Application filed January 16, 1918. Serial No. 212,147. Term of patent 7 years.

To all whom it may concern:

Be it known that I, KATHARINE S. BANNING, a citizen of the United States, residing at Los Angeles, in the county of Los Angeles and State of California, have invented a new, original, and ornamental Design for a Comfort-Bag, of which the following is a specification, reference being had to the accompanying drawings, forming part thereof.

Figures 1 and 2 are views of opposite sides of a comfort bag showing my new design.

I claim:

The ornamental design for a comfort bag, as shown.

Signed at Los Angeles, California, this 7th day of January, 1918.

KATHARINE S. BANNING.

Witnesses:

MARGARET J. SENSBACH,

MARY SHEA.
